 corporation of Delaware

Application January 1, 1943, Serial No. 470,971

12 Claims. (Cl. 123—102)

This invention relates to fuel intake pressure regulators for internal combustion engines used on airplanes. One type of such pressure regulator is disclosed in Dolza et al. application, Serial No. 449,918, filed July 6, 1942. Briefly, the Dolza pressure regulator comprises a manually operated main control lever for moving the engine throttle valve from idling position to an open position slightly less than that required for take-off and automatic pressure controlled means for moving the valve still further toward wide open position. The further opening of the valve is such that a selected engine intake pressure will be maintained at varying altitudes in predetermined relation to altitude. The automatically operated means for moving the throttle is a hydraulic servo motor operated by oil from the engine oil pressure system. Such a servo motor will not operate when the oil pressure fails or when the oil becomes congealed. Therefore this regulator provides for continuous circulation of oil from the engine and back again and provides a safety spring for returning the throttle to the range of manual control in case of cessation of oil pressure.

It is an object of the present invention to provide electrically operated means for effecting movement of the throttle valve, and a control for the electrically operated means responsive to operation of the manual means for moving the throttle valve and responsive to the pressure at the fuel intake of the engine.

Further objects and advantages of the present invention will be apparent from the following description, reference being had to the accompanying drawings wherein a preferred embodiment of the invention is clearly shown.

In the drawings:

Figs. 1 and 2 are diagrams showing various statuses of a controller arranged to be operated automatically by an electric servo motor which is not shown in these figures.

Fig. 3 is a diagram of an electric servo motor and control therefore adapted to be used with the regulator shown in Figs. 1 and 2.

Fig. 4 is a sectional view on line 4—4 of Fig. 3.

A lever 10-called the main control lever is connected with a shaft 11 which operates arms 12 and 13. The free end of arm 13 supports a pivot 14 for a bell crank lever having arms 15 and 16. The free end of arm 15 is connected by pivot 17 with a link 18 connected by pivot 19 with an arm 20, attached to a shaft 21 which operates a throttle valve 22 in a fuel intake pipe 23. Arm

16 is connected by pivot 24 with a link 25 connected by pivot 26 with levers 27 and 28. Lever 27 is connected with a shaft 29 whose axis is designated by point 30. Point 30 is located below the axis of a shaft 31 which carries a pressure selecting cam 33 and which is turned by a lever 34 connected at pivot 35 with a link 36 connected at pivot 37 with lever 12.

Cam 33 controls the position of the lever 40 10 which is pivoted at 41 and which is urged against the cam 33 by spring 42. The lower end of lever 40 is engaged by blocks 43 and 44 slidably between guides 45. Pivot 41 is supported by a bridge 46 connecting the free end blades 47 and 48 of flexible metal bellows 49 and 50 respectively having fixed ends 51 and 52 respectively. Bellows 49 is evacuated. Bellows 50 is connected by pipe 53 with the engine fuel intake. Springs (not shown) are located within the bellows 49 and 50 and these springs are so calibrated that the pivot 41 will move in a predetermined relation to changes in the engine fuel intake pressure within the bellows 50. Since bellows 50 is tied to the aneroid bellows 49, variations in external pressure only will not change the position of pivot 41.

The lever 28 is connected with a shaft 60 which is operated by the reversible electric servo motor, to be described. The operation of this motor in either direction is controlled by carbon pile resistances 61 and 62. The pile 61 confined between electrodes 63 and 65 and the pile 62 is confined between electrodes 64 and 66. Electrodes 63 and 64 are electrically insulated from the mechanism thus far described. A spring 67 is confined between block 44 and electrode 63. A spring 68 is confined between block 43 and electrode 64. When blocks 43 and 44 are located substantially midway between the electrodes 63 and 64, the pressure exerted by springs 67 and 68 will be equal, and the resistances of the piles 61 and 62 will be equal. In order that this relation may be effected, adjustments can be made by screws 69 and 70 threaded through stationary supports 71 and 72 and bearing respectively against the electrodes 65 and 66.

As will be described later in connection with Fig. 3, when the blocks 43 and 44 move toward the right to increase the compression of spring 68 and to reduce the compression of spring 67 as shown in Fig. 2, the servo motor will operate shaft 60 counterclockwise to move the arm 28 from the position 28a toward the position 28b in Fig. 2. If the blocks 43 and 44 move toward the left from mid position, the compression of spring 67 will

be increased and the compression of spring 68 will be decreased and the servo motor to rotate the shaft 60 clockwise. When block 44 is in mid-position so that the resistances of the piles 61 and 62 are the same, no rotation of shaft 60 takes place. Normally the parts stand in the position shown in Fig. 1, the throttle 22 being in idle position which, for example, is 11° from the horizontal.

If the pilot wishes to take off, he moves the main control lever 10 connected with the pilot throttle operating lever in the cockpit in a counterclockwise direction to the position 10a shown in Fig. 2. The servo motor has not yet rotated the shaft 60 from the position shown in Fig. 1, therefore the arm 28 and link 25 remain in the positions designated 28a and 25a in Fig. 2. Movement of the lever 10 to the position 10a causes arm 12 to move to 12a and pivot 14 to move to 14a in Fig. 2. Therefore bell crank lever arms move to 15a and 16a in Fig. 2. Link 18 moves to 18a, throttle lever 20 moves to 20a and throttle 22 moves to 22a which is the 51° position or 40° from idle position. This movement of lever 10 causes link 36 to move to 36a and arm 34 to move to 34a which is the dot-dash line position shown in Fig. 2; therefore cam 33 moves to 33a which is the dot-dash line position shown in Fig. 2. Spring 42 therefore causes lever 40 to move to the 40a position in Fig. 2. Blocks 43 and 44 move to the positions shown in Fig. 2 and spring 68 is additionally compressed while spring 67 is weakened. This causes the resistance of carbon pile 62 to decrease while the resistance of carbon pile 61 increases. In a manner to be explained with reference to Fig. 3, the servo motor causes shaft 60 to turn counterclockwise so that arm 28 moves left from 28a, the link 25 moves left from 25a, the bell crank lever arms 15 and 16 move, respectively, clockwise from 15a and 16a; link 18 moves right from 18a, lever 20 moves clockwise from 20a, and throttle valve 22 moves clockwise from 22a. The extent of movement of these parts for the purpose of automatically opening the throttle valve 22 beyond the manually set position 22a increases with altitude. At ground level, the automatic opening of valve 22 beyond position 22a is relatively small in order that the engine intake pressure will cause bellows 50 to expand and move lever 40 toward the left and return blocks 43 and 44 to normal position at which further opening of valve 22 by the servo motor ceases. As altitude increases, there is a tendency of the engine intake pressure to decrease accompanied by a tendency of the bellows 50 to contract accompanied by a tendency of lever 40 to move right to decrease the resistance of carbon pile 62 and to permit the increase of the resistance of carbon pile 61. Therefore the servo motor is operating to move arm 28 from position 28a toward position 28b, to move pivot 26 from 26a toward 26b, to move link 25 from 25a toward 25b, arm 16 from 16a toward 16b, arm 15 from 15a toward 15b, link 18 from 18a toward 18b, lever 20 from 20a toward 20b, in order to move valve 22 from 22a toward 22b into the positions required for maintaining intake pressure in a predetermined relation to altitude. At critical altitude, the "b" positions of all of these parts will have been reached. As critical altitude is approached, the upper end of lever 40 is being shifted toward the right due to movement of cam 33 from ground level position 33a to critical altitude position 33b. This change in position is caused by clockwise rotation of shaft 29 by movement of arm 27 from

27a to 27b which results in moving cam shaft 31 from 31a to 31b in Fig. 2. The equilibrium position of lever 40 at critical altitude is 40b. In this way the pressure selected manually is gradually reduced as the airplane ascends. This is desirable since advantage is taken of the fact that less engine power is required to exhaust the engine against the rarefied atmosphere; therefore it is not necessary to work the engine so hard at higher altitudes. In other words the engine is operated so that the indicated mean effective pressure in its cylinders will remain the same regardless of altitude.

The electrical servo motor and its control by the carbon pile resistances 61 and 62 will now be described with reference to Fig. 3. The shaft 60 to which arm 28 is connected, as shown in Fig. 2, is driven by a servo motor 80 having armature 81 in series with a wire 82 and with a clutch operating magnet 85 in series with a wire 83. Wires 83 and 82 are connected with armature 86 and 87 of generators G1 and G2 which are so connected that their armature currents oppose as indicated by arrows 88 and 89. Generators G1 and G2 are driven by shaft 90 connected with the armature 91 of a generator-operating-motor GM having a shunt field winding 92. The generators G1 and G2 are provided, respectively, with shunt field windings 94 and 95 connected in series between line wires 96 and 97 leading, respectively, from a switch 98 connected with positive terminal of battery 99 and with negative terminal of battery 99. The flow of current through shunt field 94 of generator G1 is controlled by a bypass comprising a wire 98a, the carbon pile 61 and a manually controlled variable resistance 101. The flow of current through shunt field 95 of generator G2 is controlled by a bypass including a wire 95a, the carbon pile 62 and a manually controlled variable resistance 102. The armature 91 and field 92 of motor GM are connected between the line wires 96 and 97. When the switch 98 is closed motor GM drives generators G1 and G2. The closing of switch 98 also connects battery 99 with separately excited field winding 103 of motor 80.

The current for armature 81 of motor 80 is supplied by the armatures of generators G1 and G2; therefore the direction of rotation of motor armature 81 depends on which of the generators G1 or G2 is generating the highest voltage. If, for example, the blocks 43 and 44 move right, as shown in Fig. 2, thereby causing the resistance of carbon pile 62 to decrease and the resistance of carbon pile 61 to increase, less current will flow through generator shunt field 95 and more current will flow through generator shunt field 94, and the voltage of the armature current of G1 will increase and the voltage of armature current of G2 will decrease. Therefore the current flowing in the direction of arrow 88 will overbalance the current flowing in the direction of arrow 89 and motor SM will rotate in such direction as to rotate the shaft 60 counterclockwise so that arm 28 will move from 28a toward 28b. This causes an opening of valve 22 to such position that the desired fuel intake pressure will be maintained. Therefore the position of pivot 41 will move from 41a (Fig. 2) left to 41b, and the blocks 43 and 44 will return to mid-position. The voltages of armature G1 and G2 will be equal and rotation of the motor SM will stop.

When the airplane descends it is necessary to reduce the opening of the throttle valve in order that the pressure will not be too great. If the

pressure tends to become too great, then the blocks 43 and 44 would move toward the left of midposition, thereby causing the resistance of carbon pile 61 to decrease while the resistance of carbon pile 62 increases, whereby the flow of current through shunt field 85 increases and the flow of current through shunt field 84 decreases, whereby the voltage of armature of generator G2 increases and the voltage of armature of generator G1 decreases, thereby causing the motor SM to operate in the reverse direction and the shaft 60 to move clockwise so that the arm 28 would be moved the required distance toward position 28a.

Excessive movement of arm 28 in either direction is prevented by a mechanism controlled by arm 28 acting through shaft 60. Shaft 60 is connected with an arm 112 connected by a link 113 with an arm 114 attached to the hub 115 of a gear 116 meshing with a rack 117 having a lug 118 shaped to clear the lower end of lever 40 but to engage either of the blocks 43 and 44. Assuming that a reduction of intake pressure below that selected to be maintained has occurred, thereby causing bellows 50 to contract and the blocks 43 and 44 to move to the position shown in Fig. 2, block 44 will then be located close to the left side of lug 118 as it is located in Fig. 3. When, as the result of the condition shown in Fig. 2, lever 28 is caused to move counterclockwise to open the throttle valve 22 in order to increase the intake pressure, lug 118 moves left to move block 44 to increase the pressure of spring 67 above what it would be when in the condition shown in Fig. 2. Therefore, while the throttle valve is being moved to effect a condition which will restore equilibrium by acting through the bellows 50 to return lever 40 to mid-position shown in Fig. 1, the lug 118 is acting in anticipation of the restoration to equilibrium by so acting through block 44 and spring 67 upon carbon pile 61 as to increase its resistance and to reduce the current in field 84 of generator G1, thereby decreasing the amount of voltage by which the voltage of generator G1 had exceeded G2. Therefore, the speed at which lever 28 moves counterclockwise to open the throttle valve is gradually reduced. Therefore lever 28 does not overtravel in a counterclockwise direction. In a similar manner, overtravel of lever 28 in a clockwise direction is prevented when the altitude is decreasing.

The motor 80 is mechanically connected by speed reducing gearing 84 with a clutch driving member 100 adapted to be engaged by a driven member 101 at all times connected with a shaft 110 connected by a friction clutch 111 with shaft 60. Clutch 111 will yield to permit manual operation of lever 28.

Member 101 has a brake face 102 normally contacting a fixed brake part 103 against which it is maintained by a spring 104 acting against a lever 105, pivoted at 106 and carrying a stud 107 received by a groove in member 101. Lever 105 carries an armature 108 located adjacent a core 109 surrounded by the clutch and brake controlling magnet coil 85. When the voltage impressed on motor 80 is sufficient to cause it to operate and turn the lever 28, the magnetism of coil 85 is sufficient to overcome spring 104 and to cause clutch parts 101 and 100 to be engaged and the brake parts 102 and 103 to be disengaged. When the voltage impressed on motor 80 is too low to cause its operation, the coil 85 is so weakened that spring 104 operates to disen-

gage clutch parts 100 and 101 and to engage the brake parts 102 and 103. Therefore, when the motor 80 is deenergized, shaft 60 will stop and will be retained in the position in which it was located by the motor 80 at the time it was deenergized, although the motor armature might continue rotating due to its inertia.

While the embodiment of the present invention as herein disclosed, constitutes a preferred form 10 it is to be understood that other forms might be adopted, all coming within the scope of the claims which follow.

What is claimed is as follows:

1. Apparatus for regulating the fuel intake 15 pressure of a supercharged internal combustion engine having a throttle valve, manually operable means for effecting movements of the throttle valve, a D. C. electric motor for effecting other movements of the throttle valve, and control means for the electric motor under the control of the manual means and of the pressure at the fuel intake and operable to control the direction and amount of current flow through the armature of the D. C. motor.

2. Apparatus for regulating the fuel intake 20 pressure of a supercharged internal combustion engine having a throttle valve, manually operable means for effecting movements of the throttle valve, a D. C. electric motor for effecting other movements of the throttle valve, two sources of D. C. voltage connected in voltage opposition and to the armature of the D. C. motor and means under the control of the manual means and of the pressure at the fuel intake for regulating the voltage of said two voltage sources.

3. Apparatus for regulating the fuel intake 25 pressure of a supercharged internal combustion engine having a throttle valve, manually operable means for effecting movements of the throttle valve, a D. C. electric motor for effecting other movements of the throttle valve, two D. C. generators having their armatures connected in voltage-opposition and to the armature of the D. C. motor, means for driving the generators, and means under the control of the manual means and of the pressure at the fuel intake for regulating the field excitation of the generators.

4. Apparatus for regulating the fuel intake 30 pressure of a supercharged internal combustion engine having a throttle valve, manually operable means for effecting movements of the throttle valve, a D. C. electric motor for effecting other movements of the throttle valve, two D. C. generators having their armatures connected in voltage-opposition and to the armature of the D. C. motor, means for driving the generators, two carbon pile resistances respectively in shunt with the field circuits of the generators, and means under the control of the manual means and of the pressure at the fuel intake for adjusting said resistances.

5. Apparatus for regulating the fuel intake 35 pressure of a supercharged internal combustion engine having a throttle valve, manually operable means for effecting movements of the throttle valve, a D. C. electric motor for effecting other movements of the throttle valve, means for controlling the direction and amount of current flow through the armature of the D. C. motor and including two variable resistances and means under the control of the manual means and of the pressure at the fuel intake for adjusting said resistances.

6. Apparatus for regulating the fuel intake 40 pressure of a supercharged internal combustion

engine having a throttle valve, manually operable means for effecting movements of the throttle valve, a D. C. electric motor for effecting other movements of the throttle valve, means for causing the D. C. motor to rotate in one direction or the other or to stop, said means including two variable resistances and means under the control of the manual means and of the pressure at the fuel intake for adjusting said resistances.

7. Apparatus for regulating the fuel intake pressure of a supercharged internal combustion engine having a throttle valve, manually operable means for effecting movements of the throttle valve, a D. C. electric motor for effecting other movements of the throttle valve, means for causing the D. C. motor to rotate in one direction or the other or to stop, said means including two variable resistances, a lever for adjusting said resistances, and means under the control of the manual means and of the pressure at the fuel intake for actuating said lever.

8. Apparatus for regulating the fuel intake pressure of a supercharged internal combustion engine having a throttle valve, manually operable means for effecting movements of the throttle valve, a D. C. electric motor for effecting other movements of the throttle valve, means for causing the D. C. motor to rotate in one direction or the other or to stop said means including two variable resistances, a lever for adjusting said resistances, fulcrums for the lever at spaced points thereof, means under the control of the manual means for adjusting one fulcrum and means under the control of the pressure at the fuel intake for adjusting the other fulcrum.

9. Apparatus for regulating the fuel intake pressure of a supercharged internal combustion engine having a throttle valve, manually operable means for effecting movements of the throttle valve, a D. C. electric motor for effecting other movements of the throttle valve, means for causing the D. C. motor to rotate in one direction or the other or to stop, said means including two variable resistances, a movable element for adjusting said resistances, a lever having one end connected with said movable element, fulcrums for the lever located respectively at the other end of the lever and at a point between the ends of the lever, means under the control of the manual means for adjusting the fulcrum at the end of the lever remote from the resistance-adjusting element, and means under the control of the pressure at the fuel intake for adjusting the fulcrum between the ends of the lever.

10. Apparatus for regulating the fuel intake pressure of a supercharged internal combustion engine having a throttle valve, manually operable means for effecting a movement of the throttle valve to variably regulate the intake pressure, an electric motor for effecting other movements of the throttle valve to also variably regulate the intake pressure and control means for the electric motor under control of the manual means and of the pressure in the fuel intake, said control means being operable to control the direction of movement of the throttle valve by said motor and also operable to control the amount of movement of said valve which is effected by the motor.

11. Apparatus for regulating the fuel intake pressure of a supercharged internal combustion engine having a throttle valve, manually operable means for effecting a movement of the throttle valve to variably regulate the intake pressure, an electric motor for effecting other movements of the throttle valve to also variably regulate the intake pressure and control means for the electric motor under control of the manual means and of the pressure in the fuel intake, said control means being operable to control the direction of movement of the throttle valve by said motor and also operable to control the amount of current flow through the armature of the motor so as to control the amount of movement of the throttle valve by said motor.

12. Apparatus for regulating the fuel intake pressure of a supercharged internal combustion engine having a throttle valve movable to various positions to control said intake pressure, manually operable means for selecting a pressure to be maintained and for moving the throttle valve toward the position it should occupy to maintain the selected pressure and a motor for effecting additional movements of the throttle valve to bring such valve to the required position, said motor being effective to produce other movements of the throttle valve to maintain the pressure selected under different operating conditions and control means for the electric motor under the control of the manual means and of the pressure in the fuel intake, said control means being operable to control the direction of movement of the throttle and the amount of such movement necessary to maintain the pressure selected.

EDWARD M. CLAYTON.
